(57) **CLAIM**

The ornamental design for a nose hair cutter, as shown and described.

DESCRIPTION

FIG. 1 is a perspective view of a nose hair cutter embodying the design.

FIG. 2 is a front view thereof.

FIG. 3 is a back view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a disassembled state of thereof.

FIG. 9 is an enlarged view of Part A of FIG. 8; and,

FIG. 10 is an enlarged view of Part B of FIG. 8.

The dash-dot-dash broken lines illustrate the boundaries of the enlarged portions and form no part of the claimed design.
